UNITED STATES PATENT OFFICE.

ARTHUR J. ENGMAN, OF CANTON, OHIO.

METAL DOOR.

Application filed May 24, 1922. Serial No. 563,228.

To all whom it may concern:

Be it known that I, ARTHUR J. ENGMAN, a citizen of the United States, residing at Canton, in the county of Stark and State of

Ohio, have invented a new and useful Metal Door, of which the following is a specification.

This invention relates to metal doors and particularly to this class of devices in which 10 a translucent panel or light is employed.

The principal object of the invention is to produce a construction which will have the maximum rigidity, at the same time employing a minimum number of parts, there- 15 by effecting a reduction in both the amount of material used and the labor necessary to assemble my device.

In the drawings, in which similar numerals of reference indicate corresponding 20 parts;

Fig. 1 is a fragmentary view of a door showing portions of the top and one of the side rails or stiles, a corner of the glass panel or light being shown therein.

25 Fig. 2 is a section on the line 2—2 of Fig. 1, looking in the direction of the arrow.

Fig. 3 is a fragmentary perspective of portions of the panel moulding, stile and binder moulding, spaced apart.

30 At 1 is indicated a vertical side rail or stile of a door. One edge of the sheet forming the stile is bent inwardly, forming a flange 2. Spot welded or otherwise secured to the inner face of the stile at a point 35 spaced slightly from the flanged edge 2, is the portion 3 of a binder strip or moulding. As will be clearly seen in the drawing, the portion 3 of the binder is the edge thereof farthest from the flange 2. At the edge of 40 the portion 3 nearest the flange 2, the binder moulding is bent at right angles and extends inwardly as at 4, and is then bent and extends toward the flange 2 and is parallel with the face of the stile as indicated at 5.

45 Extending from the portion 5 and toward the adjacent side of the stile is a portion 6 which is parallel with the portion 4, the moulding being again bent and terminating in a flange 7 which is parallel with the face 50 of the stile and spaced slightly therefrom.

In direct alinement with the above described binder and spot welded or otherwise secured to the opposite side of the stile, is a second binder which is identical in every detail 55 with the one described.

By the peculiar arrangement of the por-

tions 4, 5 and 6, a groove 8 is formed in the binders and fitting within the groove in the first mentioned binder is the in-turned flanged end 9 of the member 10 which forms 60 one half of the panel moulding. The portion 11 of the member 10 which is adjacent the flange 9, fits within the space between the flange 7 and the face of the stile and is bent as at 12 to fit between the extremity of 65 the said flange 7 and the flange 2. As clearly seen in Figs. 2 and 3, the member 10 is shaped to describe an arc and is then bent backwardly as at 13, the portion 13 forming one face of the channel within 70 which the glass panel is secured.

Extending from the portion 13 to the opposite side of the stile is a web 14 and formed in the said web in vertical alinement, is a plurality of threaded apertures 75 15 which are for a purpose to be hereinafter set out. The web 15 terminates in a laterally extending portion which in turn is bent to fit between the adjacent side of the stile and the flange 7 on the attached binder and 80 is then bent inwardly to form a flange 16 which fits within the groove in the said binder.

The sheet forming the side of the stile opposite the side carrying the flange 2, is 85 bent inwardly at a point in direct alinement with the said flange and then develops into an arcuate portion 17 which reaches to the panel 18 and is then bent backwardly as at 19 and completes the groove for the 90 said panel. A plurality of apertures 20 are formed in the portion 17 in alinement with the threaded apertures 15 and inserted through the apertures 20 and engaging the threads of the apertures 15, are screws 21 95 which, when tightened, draw the portion 19 into engagement with the panel. An extremely simple and rigid construction is thus effected.

By extending the one side of the sheet 100 forming the stile and bending it to form one half of the panel moulding, the possibility of the glass becoming loose and rattling or breaking from vibration is eliminated.

Having now described my invention, what 105 I claim is:

1. In a device of the character described, a sheet of metal bent to form a stile, a pair of binders secured to the opposite, inner walls of said sheet, a strip secured by said 110 binders and bent to form one half of a panel moulding, one side of said sheet being

extended and forming the opposite half of said panel moulding.

2. In a metal door, a sheet of metal bent to form a stile, a pair of binders secured to the opposite inner walls of said stile, a strip secured by said binders and bent to form one half of a panel moulding, one side of said sheet being extended and forming the other half of said panel moulding,

screws inserted through said second half of 10 said moulding and threaded through said strip and arranged to hold both halves of said moulding against the panel when so positioned.

In testimony that I claim the above I have 15 hereunto subscribed my name.

ARTHUR J. ENGMAN.
